UNITED STATES PATENT OFFICE.

JOSEPH HUBER, JR., OF NOKOMIS, ILLINOIS.

CHECK HOLDER.

Application filed January 17, 1928. Serial No. 247,400.

This invention appertains to attachment for mining cars and more particularly to a novel holder for mine car checks.

One of the primary objects of this invention is to provide novel means which can be readily connected to the side of a mining car for effectively holding the mine car checks against loss and which will permit the easy placing of the check in position and 10 the quick removal thereof by authorized persons.

Another salient object of the invention is the provision of a mine car check holder comprising a body plate for connection directly with the side of a mine car having resilient means pivotally associated therewith and forming in connection with the body plate jaws for engaging the check, means being provided for permitting the 20 quick release of the check by pressure on the resilient means.

A further object of the invention is the provision of novel means for connecting the holding plate with the body plate whereby 25 the use of hinge barrels and hinge pins is entirely eliminated.

A still further object of the invention is to provide a novel mine car check holder of the above character, which is durable and 30 efficient in use, one that is simple and easy to manufacture and one which can be placed upon the market and incorporated with a mine car at a low cost.

With these and other objects in view, the 35 invention consists in a novel construction, arrangement and formation of parts, as will be hereinafter more specifically described, claimed and illustrated in the accompanying drawings, in which drawings,

40 Figure 1 is a side elevation of the mine car check holder,

Figure 2 is a top plan view of the same,

Figure 3 is a rear elevation of the check holder,

45 Figure 4 is a front elevation of the check holder, and

Figure 5 is a transverse section through the check holder taken on the line 5—5 of Figure 2 looking in the direction of the arrows.

Referring to the drawings in detail, where in similar reference characters designate corresponding parts throughout the several views, the letter A generally indicates the 55 improved mine car check holder which comprises a body plate 10, a gripping plate 20,

and novel means 30 for holding the gripping plate in proper frictional contact with the body plate.

The body plate 10 is constructed from sheet metal of the desired gauge and includes a flap holding portion 11 and a right angularly extending depending attaching portion 12. This attaching portion 12 is provided with suitable openings 13 for the 60 reception of fastening elements (not shown) whereby the entire device can be readily secured to the side of a mining car at the desired point. The holding portion 11 of the body plate is of a greater length than the 65 attaching portion 12 and the opposite side edges thereof adjacent to but spaced from the attaching portion 12 are provided with notches or cut out portions 14, the purpose of which, will be later described. The holding portion 11 forwardly of the notches 12 and at the longitudinal center thereof is provided with an opening 15, the purpose of which will also be later described.

The gripping plate 20 forms one of the 70 salient features of this invention and includes a flat gripping main plate 21 having a depending right angularly extending jaw 22 formed thereon. This jaw 22 extends transversely of the holding plate portion 11 of the body plate 10. The rear end of the gripping plate 21 has formed thereon the angularly extending finger grip operating portion 23 and it is to be noted that this portion 23 is of a less width than the gripping 75 plate portion 21 and that the finger grip portion 23 is connected with the gripping plate portion 21 by an arcuate bight portion 24 which forms the fulcrum on which the gripping member 20 rocks. Right angularly extending depending side tongues 25 are struck down from the sides of the gripping plate 21 on opposite sides of the bight 80 85 90 95 100 105 110 115 120 125 130 135 140 145 150 155 9725 9730 9735 9740 9745 9750 9755 9760 9765 9770 9775 9780 9785 9790 9795 9800 9805 9810 9815 9820 9825 9830 9835 9840 9845 9850 9855 9860 9865 9870 9875 9880 9885 9890 9895 9900 9905 9910 9915 9920 9925 9930 9935 9940 9945 9950 9955 9960 9965 9970 9975 9980 9985 9990 9995 9999 10000 10005 10010 10015 10020 10025 10030 10035 10040 10045 10050 10055 100

openings 15 and 26 so as to permit the rocking movement of the gripping plate 20, as will be later described. An expansion coil spring 32 is placed upon the shank of the 5 bolt with the inner end thereof in engagement with the lower face of the holding plate portion 11 and its opposite ends in engagement with an adjusting nut 33 threaded upon the shank of the bolt. Thus, it can be
10 seen that the resilient means 30 function to normally hold the gripping plate portion 21 toward the holding plate 11 with the jaw 22 in contact with said holding plate portion 11. In reality the holding plate portion 11 and
15 the gripping plate portion 21 constitutes jaws for receiving therebetween the mine car check indicated by the reference character B in Figure 1 of the drawings. Not only does the resilient means 30 act to hold
20 the plate portion 21 toward the holding plate 11 but also functions to hold the entire member 20 in proper position and permit the rocking of this plate without displacement thereof.
25 In use of the improved device, the same is attached to the side of a mining car, as described, and when it is desired to place a mine car check on the car, pressure is applied to the operating portions 23 by the
30 operator which will swing the jaw 22 away from the holding plate 11 and thus allow the insertion of the mine car check between the jaw and the holding plate. Upon release of pressure by the operator, the mine
35 car check will be effectively held in place between the holding plate and the gripping jaw.

To release the check, it is merely necessary to again apply pressure to the finger grip 40 operating portion 23, which will permit the quick release of the mine car check.

From the foregoing description, it can be seen that a simple and effective device embodying a minimum number of parts has 45 been provided for permitting the quick association of a mine car check with a mine car

without danger of accidental displacement of the check from the car. This constitutes a decided improvement over the method now generally employed in connecting mine car 50 checks with mine cars, namely of hanging the checks upon a suitable hook or bracket.

Changes in details may be made without departing from the spirit or the scope of this 55 invention, but

What I claim as new is:

1. A check holder comprising a body plate including a flat holding portion, the side edges of the holding plate portion having notches therein, a gripping plate including a flat contact portion and an angularly extending operating portion, depending tongues carried by contact plate portion disposed in said notches, and resilient means normally holding the contact plate portions toward the holding plate portion and said gripping plate in proper position on said body plate.

2. A car check holder comprising a body plate including a holding plate portion and a right angularly extending attaching plate portion, the side edges of the holding plate portion having notches formed therein, a gripping plate including a contact plate portion and an angularly extending operating 75 finger grip portion, said contact plate portion and operating grip portion being connected together by an arcuate bight portion depending tongues formed on the sides of said gripping plate disposed in said notches 80 in the holding plate, the holding plate and the contact plate portions having aligned bolt receiving openings therein, a headed bolt placed in said openings with the head thereof for engagement with one of said plate portions, an expansion spring about said bolt engaging the other of said plate portions, and adjustable means on said bolt engaging said spring.

In testimony whereof I affix my signature.

JOSEPH HUBER, JR.
